UNITED STATES PATENT OFFICE.

LEON WITTELS, OF NEW YORK, N. Y.

BLUE-PRINT-PAPER HOLDER.

1,010,472.

Specification of Letters Patent.

Patented Dec. 5, 1911.

Application filed January 20, 1911. Serial No. 603,688.

To all whom it may concern:

Be it known that I, LEON WITTELS, a citizen of Austria, and residing at New York, in the county of New York and State of New York, have invented certain new and useful Improvements in Blue-Print-Paper Holders, of which the following is a specification, such as will enable those skilled in the art to which it appertains to make and use the same.

This invention relates to holders for blue-print paper, and the object thereof is to provide an improved device of this class which is designed to receive a roll of blue-print paper and which is so constructed as to exclude light, dust and dirt from the paper, and from which a predetermined amount of the paper may be withdrawn and detached whenever desired for use without opening the holder and without exposing the paper therein to the light; and with this and other objects in view the invention consists in a device of the class specified, constructed as hereinafter described and claimed.

The invention is fully disclosed in the following specification, of which the accompanying drawing forms a part, in which the separate parts of my improvement are designated by suitable reference characters in each of the views, and in which:—

Figure 1 is a perspective view of my improved blueprint paper holder; Fig. 2 a front view showing the front part of the holder detached and showing a roll of paper mounted therein; Fig. 3 a transverse section on the line 3—3 of Fig. 2; Fig. 4 a perspective view of a detail of the construction; and, Fig. 5 a perspective inside view of one end portion of the holder and showing a modification of the means for supporting the roll of paper therein.

In the practice of my invention, I provide an oblong box or case *a* which is preferably rectangular in cross section, and comprises a top *a*², a back *a*³, a bottom *a*⁴ and ends *a*⁵. The box or case *a* is open at the front, and the front edge of the top *a*² is provided with an upwardly directed flange *a*⁶, and the front edges of the ends *a*⁵ are provided with inwardly directed keepers *a*⁷ designed to receive and hold a removable front *a*⁸ which is adapted to be dropped into the keepers *a*⁷, and the re-

movable front *a*⁸ is provided at the top 55 thereof with a backwardly and downwardly directed lip or flange *a*⁹ which overlaps the flange *a*⁶, and which supports the front *a*⁸, as will be readily understood, and pivoted to the top *a*² of the box or case at *b* is a 60 spring hook *b*² designed to be turned over and engage the top of the removable front *a*⁸ and hold it in position, or prevent its upward movement.

The front edge of the bottom *a*⁴ of the 65 box or case is provided with a downwardly directed flange *c* to the ends and the back side of which are secured vertically arranged keepers *c*², and the flange *c* is cut out at the bottom edge thereof to form a 70 longitudinal recess *c*³ which is closed by an oblong vertically movable plate *d* provided with end members *d*² which pass through and are vertically movable in the keepers *c*², and said plate *d* is provided at 75 its bottom edge with a backwardly directed lip or flange *d*³.

The removable front *a*⁸ is provided with a downwardly directed extension *a*¹⁰, the vertical width of which below the bottom *a*⁴ 80 of the box or case is approximately the same as the vertical width of the parts *c* and *d*, when said part *d* is in its normal position, as shown in Figs. 3 and 4, and the bottom part of the removable front *a*⁸ is provided, in the 85 form of construction shown, with a horizontal bead member *a*¹¹ which gives strength and rigidity to said removable front, the latter being preferably composed of sheet metal as is all the rest of the box or case *a*. 90

Secured centrally of the inner sides of the end portions *a*⁵ of the box or case are ear members *e*, one of which is shown in dotted lines in Fig. 3 and both of which are shown in full lines in Fig. 2, and these ear 95 members serve to support a roller *f* on which the blueprint paper *g* is wound, and the ears *e* may be constructed in any desired manner, but in Fig. 5 of the accompanying drawing, I have shown at *e*² the form of said ears that 100 I prefer, said form consisting of a flat vertically arranged member *e*³, the lower end of which is provided with a forwardly and upwardly directed hook *e*⁴, and with this form of construction, all that is necessary 105 in placing the roll of paper in the case or holder is to remove the front *a*⁸ and then move said roll of paper backwardly into

the box or case until the end trunnions f^2 of the roller f strike the upright parts e^3 of the ears e^2 , and then drop the trunnions e^2 into the hook members e^4 . I also employ 5 spring fingers h provided at their upper ends with backwardly directed extensions h^2 which are passed through corresponding keepers h^3 secured to the inner side of the top a^2 of the box or case, and the spring 10 fingers h extend downwardly, transversely of the roll of paper, and the lower ends thereof overlap the flange c at the front edge of the bottom a^4 of the box or case, as clearly shown at h^4 in Fig. 3, and in practice, the 15 free end g^2 of the paper after the roll has been inserted into the box or case is pulled down to the bottom of the vertically movable plate d and the removable front a^8 is placed in position. The bottom portion of 20 the removable front a^8 presses on the lower ends of the spring fingers h , and said spring fingers press on the paper, and if the roll of paper is large enough the said spring fingers will also press thereon, and this 25 holds the roll of paper stationary, as will be readily understood, and whenever it is desired to tear off a piece of paper the vertically movable plate d is moved upwardly by means of a finger or fingers and the end 30 edge of the paper is grasped between the thumb and fingers and the paper is pulled down to the desired extent and is torn off over the bottom edge of the front a^8 of the box or case as will be readily understood. I 35 also connect with the removable front a^8 of the box or case and centrally thereof a spring operated measuring tape device i , and the end i^2 of the measuring tape may be drawn out and pulled down at the same time that 40 the end of the paper is pulled out of the box or case, as above described, and the amount of paper so pulled out and torn off may thus be measured as will be readily understood.

The measuring tape device i is circular in 45 form and, in practice, I secure to the front a^8 of the box or case a vertically arranged keeper j and provide a spring j^2 which is inserted thereinto and provided with a circular hook member j^3 into which the tape 50 device i is inserted, and said tape device may be detached as may also the spring j^2 whenever desired.

The ends of the box or case are also provided with triangular keepers k in which 55 are pivoted as shown at k^2 L-shaped brackets k^3 , and which may be turned in the position shown in full lines in Figs. 1 and 2, and by means of which the paper holder may be secured to a vertically arranged support, or 60 said L-shaped bracket members k^3 may be turned into the position shown in dotted lines in Fig. 1 in which position the paper holder may be secured to a horizontal support.

65 With the herein described construction,

it will be seen that when the paper holder is in use it is completely closed at all points and the light excluded therefrom as is also all dust or dirt, and the vertically movable plate d^2 connected with the flange c aids in excluding the light from the paper and also facilitates the grasping of the free edge of the paper in the operation of pulling said paper out and tearing it off, and it will be apparent that my improved blueprint paper holder may be made of any desired dimensions. 75

The construction of the end supports for the box a is not claimed in this case, but is made the subject of a divisional application 80 filed July 10, 1911, Serial No. 637,653.

Having fully described my invention, what I claim as new and desire to secure by Letters Patent, is:—

1. A blueprint paper holder box or case 85 provided with a vertically movable and removable front, the front edge of the bottom of the holder being provided with a downwardly directed flange with which is connected a vertically movable member 90 which normally extends below said flange, and the bottom edge of the front being also extended downwardly to the bottom of said vertically movable member.

2. A blueprint paper holder box or case 95 provided with a vertically movable and removable front, the front edge of the bottom of the holder being provided with a downwardly directed flange with which is connected a vertically movable member which 100 normally extends below said flange, and the bottom edge of the front being also extended downwardly to the bottom of said vertically movable member, and the front edge of the top being provided with a raised flange and said front being provided with a backwardly and downwardly directed lip adapted to rest on said flange.

3. A blueprint paper holder box or case open at the front, the front edge of the top 110 of said box or case being provided with an upwardly directed flange, the ends of said box or case being provided with keepers and a front adapted to be passed downwardly through said keepers and provided at its 115 top edge with a backwardly and downwardly directed lip adapted to rest on said flange, the front edge of the bottom of the box or case being also provided with a downwardly directed flange having a vertically movable member and the bottom edge of the front being extended downwardly flush with said vertically movable member.

4. A box or case of the class described, designed to receive a roll of blueprint paper, 125 said box or case being open at the front and the bottom thereof being provided at its front edge with a downwardly directed flange, spring fingers adapted to be secured within the box or case and to the top there. 130

of and which extend downwardly and rest on said flange, and a vertically movable and removable front for said box or case which when in position overlaps said flange and 5 presses on said spring fingers.

In testimony that I claim the foregoing as my invention I have signed my name in

presence of the subscribing witnesses this 18th day of January 1911.

LEON WITTELS.
